CLAIM

The ornamental design for an electronic device with graphical user interface, as shown and described.

DESCRIPTION

FIG. 1 is a front view of an electronic device with graphical user interface showing the claimed design; and, FIG. 2 is another embodiment thereof.

The outer broken lines in the figures show an electronic device, and form no part of the claimed design.

The other broken lines in the figures show portions of the graphical user interface that form no part of the claimed design.
